UNITED STATES PATENT OFFICE.

C. B. GUY, OF LYBRAND, IOWA.

IMPROVEMENT IN FORCE-PUMPS.

Specification forming part of Letters Patent No. 43,684, dated August 2, 1864.

To all whom it may concern:

Be it known that I, C. B. GUY, of Lybrand, in the county of Allamakee and State of Iowa, have invented a new and Improved Pump; and I do hereby declare that the following is a full, clear, and exact description of the same, reference being had to the accompanying drawings, making a part of this specification, in which—

Figure 1 is a side sectional view of my invention, taken in the line *xx*, Fig. 2; Fig. 2, a plan or top view of the same.

Similar letters of reference indicate corresponding parts in the two figures.

This invention is more especially designed for domestic purposes, and has for its object the elevating of water from springs, wells, &c., and forcing it to any convenient distance or height by a very moderate expenditure of power and comparative inexpensive means.

The invention consists in the employment or use of a chamber provided with a piston and valve, and having a force or eduction pipe communicating with it provided with a check-valve, the above parts being used in connection with a loaded lever applied to the piston-rod and a windlass connected with said lever, all being arranged as hereinafter set forth.

To enable those skilled in the art to fully understand and construct my invention, I will proceed to describe it.

A represents a chamber, which may be of quadrilateral, cylindrical, or other form, provided with a piston, *B*, and having a valve, *a*, in its bottom opening upward. *C* is a force or eduction pipe, which communicates with the lower part of *A*, and is provided with a check-valve, *b*, to prevent the water forced into *C* from passing back again into *A*. These parts constitute the ordinary force pump, and

therefore do not require a minute description.

The piston *B* has its rod *D* attached to it by a joint, *c*, and the upper end of said rod is connected by a joint, *d*, with a lever, *E*, the fulcrum *e* of which is at the upper end of an upright, *F*. To one end of the lever *E* there is attached a cord, *H*, which passes underneath guide pulleys *f f*, and is connected to a windlass, *I*. The force or eduction pipe *C* may be carried to any convenient distance or height, where it is designed to have the water conveyed and discharged, and the windlass *I* may be near the discharge-orifice of said pipe *C*. The pump is submerged—at least, its lower end—in a well, spring, or reservoir, from which the water is to be drawn, and the weight *G* has a tendency to draw up the piston *B* and to cause the water to enter *A* through the valve *a*. The piston, when forced down in *A* by turning the windlass *I*, forces the water from *A* through the pipe *C*, and when the windlass is released the weight *G* again raises the piston *B* and causes water from the well, spring, or reservoir to enter *A*, from which it is again forced out through *C* when the piston is depressed. Thus by this simple and inexpensive arrangement water may be elevated and forced to any desired distance or height.

Having thus described my invention, what I claim as new, and desire to secure by Letters Patent, is—

The pump, in combination with the force or eduction pipe, loaded lever, and windlass, all arranged to operate in the manner substantially as and for the purpose herein set forth.

C. B. GUY.
